STACKABLE MARBLE RACEWAY

William Arthur Dart, Mason, Mich.

Application April 4, 1958, Serial No. 50,335

Term of patent 14 years

(Cl. D34—15)

I claim:

The ornamental design for a stackable marble raceway, as shown.
